UNITED STATES PATENT OFFICE.

MAX LANGER, OF CHARLOTTENBURG, NEAR BERLIN, GERMANY, ASSIGNOR TO SIEMENS & HALSKE, A.-G., OF SIEMENSSTADT, NEAR BERLIN, GERMANY, A CORPORATION OF GERMANY.

TELEPHONE SYSTEM.

1,322,247.

Specification of Letters Patent.

Patented Nov. 18, 1919.

Application filed June 23, 1914, Serial No. 846,813. Renewed April 10, 1919. Serial No. 289,134.

To all whom it may concern:

Be it known that I, MAX LANGER, a citizen of the German Empire, and residing at Charlottenburg, near Berlin, Germany, have 5 invented certain new and useful Improvements in Telephone Systems, of which the following is a specification.

My invention relates to telephone systems in which connections are established 10 over selectors and testing takes place over the talking wires.

The connections for the switches and the trunk lines between the switches in telephone systems worked automatically or 15 semi-automatically are generally made by means of three branches. The branches generally known as the *a*-branch and the *b*-branch are used for adjusting the switches and for the talking service, while the third 20 branch known as the *c*-branch or the private line is used for testing, engaging, releasing and like operations. In order to save the expense of the third branch for trunk lines between offices located a long distance apart, 25 translators may be connected into circuit at the outgoing end of the trunk line, say in the manner described in the German Patent 205268. The switches are then arranged for three branches, but the trunk line has 30 two branches. For simplifying the switches it has also been proposed to test over the talking branches. In this case the talking line runs over the testing contact of the switch, as described, for example, in the 35 United States Patent 709739 to Albert M. Bullard, dated Sept. 23, 1902. In consequence of the resistances being exactly balanced the testing contact is exactly at the 40 potential of the testing battery during the conversation. As no current flows through the testing relay the conversation is not disturbed by troublesome clicking noises.

This arrangement is dependent, however, 45 on the exact equalization of the resistances and cannot be employed when a switch, *e. g.* a selector, is to be used sometimes for a connection in its own office and at other times for a connection to a remote office, for in 50 this case the very different resistances of the trunk lines come into play.

A primary object of my invention is to 55 enable the switches and the trunk lines to be made for two branches, and to enable testing to take place over the talking branches without regard being paid to the

various resistances at different times, *e. g.* as when connections are made in the home or to a remote office.

To this end, I arrange that on those sections of the two talking wires, over which 60 testing is to take place, falls of potential of equal magnitude are produced in the same direction during the conversation. Then, when testing on a busy line through the testing relay, which is bridged 65 between two symmetrically located points of the talking wires, no current flows and no disturbance of the conversation is caused.

Connections are known, in which the lines between the switches are disconnected from 70 the battery during the conversation. In this case also, when a testing coil is connected over such a line no current can arise.

The falls of potential on the two talking wires are unequal during the adjustment of 75 the switches and also, under certain circumstances, during metering, releasing and like operations. Another object of my invention is to provide that regular testing 80 may take place on lines over which any service operations affecting the switches are taking place at the moment of testing. It is true that currents will then flow through the testing coil, but I select the resistance conditions on the talking wires such that the 85 service operations remain undisturbed and that the current flowing through the testing relay does not suffice for energizing it.

Arrangements are also known, in which 90 during the adjustment for lifting the selectors, for example, only the *a*-branch is used, while the *b*-branch is currentless, and in which for revolving the selectors only the *b*-branch conducts current while the *a*-branch is currentless. In this case no current 95 is present in the testing relay as the one talking branch is isolated or is weakened by high resistances.

To these and other ends described hereinafter, my invention consists in the construction, arrangement and combination of parts described hereinafter and pointed out in the claims.

One illustrative embodiment of my invention and a modification thereof are diagrammatically represented by way of example in the accompanying drawings, wherein:—

Figures 1, 2 and 3 show a telephone system in which the current impulses are sent through ground connections of the talking 110

wires to the subscriber's station over the one *a*-branch, while a current flows permanently over the other branch *b*.

Similar reference characters designate 5 like parts in all the figures.

Referring to Figs. 1, 2 and 3 the system shown operates as follows:—

When the receiver is removed from the switch hook at the station N_1 the following 10 circuit is closed: ground, battery, left hand winding of relay R , back contact t_3 , line conductor *a*, station N_1 , line conductor *b*, back contact t_2 , right hand winding of relay R , ground. When the wipers of the line 15 switch VW are advanced until the private wiper cv engages an idle trunk line, a circuit is completed from ground through battery, working contact r_1 , in parallel through the relays T and z , wiper cv , conductor *c*, resistance w_1 , in parallel through resistance w_2 , back contact m_1 to ground, and through relay C , primary off normal contact k_1 to ground. In this circuit the relays T and C are energized and, therefore, the working 20 contacts t_6 , t_7 closed. Consequently the following circuit is completed: ground, battery, relay A , left hand winding of the differentially wound relay X , trunk line *a*, working contact t_6 , station N_1 , working contact t_7 , trunk line *b*, right hand winding of 25 relay X , relay B , ground.

The calling subscriber now operates his calling dial in the usual manner thereby grounding the relay B at the station N_1 . 30 When the relay B is momentarily deenergized the differentially wound relay X is energized. As the calling dial returns to its normal position, the relay D is again energized by the following circuit: ground, 35 battery, working contact x_1 , relay B , ground. By closing the make contact x_2 the relay X also prepares the circuit over ground, battery, lifting magnet H , contact x_2 , contact a' of relay A , shaft contact wh_1 and ground for 40 the lifting magnet H . The current impulses sent over the *a*-branch on the return of the dial are transmitted by the relay A , in consequence of its opening and closing its break contact a_1 , to the lifting magnet H of the 45 first selector I GW.

On the return of the dial into its normal position the ground at the station is removed and the relay X releases its armature, while the relay B remains energized. 50 During the lifting impulse, the contact k_1 in the circuit of the relay C opened at the first step of the shaft. The relay C remains grounded, however, over its own contact c_1 , the contact x_3 and the contact m_2 . On the 55 relay X being deenergized at the termination of the first series of impulses the relay C also releases its armature owing to the contact x_3 being opened. The rotary magnet D is now energized over ground, battery, in- 60 terrupter U , relay D , contact b_1 , contact c_2

and ground and rotates the switch arm of the first selector I GW until the relay C is energized again. This occurs on the switch arms J_1 and J_2 arriving on a trunk line VL leading to a free second selector II GW, a 70 second coil 2 of the relay C being bridged by the closed make contact b_2 of the constantly energized relay B over the two talking wires leading to the next selector. The coil 2 of the relay C thus serves as a test relay. When the switch arms J_1 , J_2 arrive on a free trunk line VL a circuit for the relay A_2 and the test coil 2 of the relay C is closed over the following circuit, viz: ground, battery (in the second selector II 75 GW), relay A_2 , end contact k_2 , contact p_1 , switch arm J_1 , contact b_2 , relay C , contact c_3 , switch arm J_2 contacts p_2 , k_3 , a_2 and ground. On the relay C being energized the circuit of the rotary magnet is broken at the contact 80 c_2 , so that the first selector stops. The relay C simultaneously closes its contacts c_1 , c_4 and c_5 . The talking wires are connected by the contacts c_4 and c_5 to the second selector II GW and the test coil 2 is disconnected at the contact c_3 . The relay C now 85 remains energized in the circuit over ground, battery, *c*-branch of the preselector VW , resistance w_1 , coil 1 of relay C , contact c_1 , the shaft contact wh_2 closed at the first rotary 90 step of the selector, contact m_2 and ground until release takes place.

On the relay A_2 in the test circuit being energized the contact a_2 is reversed from ground to the contact a_3 , and the *b*-branch of the connection over the relay B_2 is thereby connected to the battery. The excitation of the relay B_2 causes the junction line to be busy. The test coil C of any selector which now tests cannot receive any current because the two branches *a* and *b* are connected over the relays A_2 and B_2 to the same pole of the battery. When the subscriber rotates his dial a second time the relays A and X are energized, whereby both the branches 100 *a* and *b* in the first selector I GW are grounded. The relay A closes the contact a_4 and the relay X closes the contact x_4 . On the return of the dial of the dial switch N_1 the subscriber's branch *a* becomes currentless 105 and the relay A is deenergized. The contact a_4 opens as frequently as the branch *a* is broken in the dial switch N_1 , and the relay A_2 releases its armature just as often. The circuit over the *b*-branch for the relay B_2 remains established over ground, battery, relay B_2 , contacts b_3 , p_2 , switch arm J_2 , contacts c_5 , resistance w_3 or contacts a'_4 , x_4 , ground, 110 however, and the contact b_4 in the circuit ground, battery, lifting magnet H_2 , contacts b_4 , a_5 , and ground for the lifting magnet H_2 of the second selector II GW remains closed. The impulses are transmitted by the make contact a_5 of the relay A_2 to the lifting 115 magnet. During the interruptions in the 120 125 130

a-branch for the current impulses and during each deenergization of the relay A_2 it is true that the contact a_2 is also closed. This, however, exercises no further action on the 5 switching operation. On the return of the dial into its normal position the deenergized relay X disconnects the ground from the b-branch of the trunk line at contact a_4 , so that the relay B_2 is deenergized. While the 10 b-branch is currentless the relay A_2 remains energized over ground, battery, relay A_2 , resistance w_4 , contact p_1 , switch arm J_1 , contacts c_4, a_4 , resistances w_5, w_6 , contact s_1 and ground, and holds its make contact a_6 closed. 15 The following circuit for the rotary magnet D_2 is thereby established, viz: ground, battery, interrupter U'_2 , relay D_2 , contacts a_6, p_3, b_5 , and the contact k_4 closed at the first lifting step of the shaft, and ground, 20 and the switch arms J_3 and J_4 of the second selector II GW are rotated. This circuit remains established until the contact p_3 opens. The contact b_5 in the same circuit remains closed because the relay B_2 does not 25 attract its armature again before the relay P_2 is energized. The make contact v_1 in the b-branch in the first selector is closed, before the relay B_2 is energized, by means of a relay V which is energized in the circuit:—ground, battery, relay V , contact a_5 , ground, this relay V being energized during the energization of the relay X over its make 30 contact a_5 , and ground is thereby connected over resistance w_1 and contact s_1 to the b-branch of the trunk line. The relay B_2 is disconnected, however, from the b-branch both at contact b_3 and also at the off normal contact k_3 , because this contact k_3 opened at 35 the first lifting step of the shaft.

40 The test circuit of the second selector II GW is as follows:—contact arm J_3 contacts a_7, b_6 , relay P_2 , switch arm J_4 . The selector advances until it finds a free third selector. The disengagement of a third selector is indicated exactly like the disengagement of a 45 second selector by a make contact a_{14} of the relay A_3 being grounded and the a-branch of the trunk line being connected over the relay A_3 of the third selector to the battery. 50 When a free third selector is found the following circuit is established, viz: ground, battery in the third selector III GW, relay A_3 , the a-branch of the trunk line, switch arm J_3 , make contact a_7 of the energized relay A_2 , break contact b_6 of the deenergized relay B_2 , relay P_2 , switch arm J_4 , b-branch of the trunk line, contact a_{14} , ground in the 55 third selector III GW. The relay P_2 in this circuit is energized and the circuit for rotating the rotary magnet D_2 is thereby opened at contact p_3 . The second selector II GW remains stationary. The engaged line to the third selector is busy as before, and the second selector II GW is busy owing 60 to the relay A_3 attracting its armature and

switching over the b-branch of the trunk line from ground to battery, so that the two branches of the trunk line are connected to the same pole. When the relay P_2 in the second selector is energized it reverses the contacts p_1 and p_2 and closes the contacts p_4, p_5 and p_6 . The following bridge is thereby placed over the talking wires in the second selector, viz: a-branch of the trunk line, contacts p_5, p_6, P_1 , relay A_2 , relay B_2 , contact p_4 , relay P_2 , b-branch of the trunk line. The talking line is connected through at the contacts p_5 and p'_2 . The resistance of this talking bridge is several thousand ohms, so that no appreciable loss of talking current 70 is caused. The bridge is connected in order to be able to exercise an influence on the releasing magnet of the second selector over the talking wires. This influence must take effect over the talking wires because no auxiliary branches exist. Release is effected on the relays A_2 and B_2 being simultaneously deenergized. Consequently, in the following periods of series of impulses at least one of the two relays A_2 and B_2 must remain energized. The bridge to be connected over the contacts a_7, b_6 and the relay P_2 is not made during the subsequent series of impulses because the condition of the two relays A_2 and B_2 subsequently no longer admits of the contacts a_7 and b_6 being closed simultaneously. 80

The object of the resistances w_3 to w_7 is to cause the busy trunk line between the first and second selectors to appear busy during the emission of impulses. The testing of the first selector with the coil C is based on both branches of busy lines being connected to the like pole of the battery, whereas in the case of the free lines in the following selector the one branch is connected to the battery and the other to ground. During the emission of impulses, however, as mentioned above the b-branch is connected to ground, i. e. over the contact a_4 in the first 90 selector, while the a-branch is periodically connected to the battery when the impulse contact a_4 is open, but is connected to ground over the contact a_4 when the contact a_4 is closed. As long as the contact a_4 is open 100 during a series of impulses a testing selector could connect its test coil C in parallel with the contact arms J_1 and J_2 and the following circuit would be established for the testing selector, viz: ground, battery of the engaged second selector, relay A_2 , contacts b_7, p_1 , switch arm J_1 of the first selector, parallel connection of the bank of contacts J_1 of the testing selector, the coil C of the testing selector, the switch arm J_2 of the testing selector, the multiple connection at the banks of contacts of the selector, the switch arm J_2 of the selector I GW shown in the drawing, contact a_4 in the illustrated selector, and ground. This would cause a double connec- 110

115

120

125

130

- tion. To prevent this, at the moment the contact a_4 opens the contact a'_4 also opens. The resistance w_3 is now so great that the relay B_2 at the illustrated selector still just holds its armature because it was previously energized, but that a test relay C in the above-described test circuit does not receive sufficient current over the resistance w_3 for attracting its armature.
- 10 At the moment of the change from lifting to rotation of the second selector, *i. e.* at the moment when the contact x_4 has opened after the emission of impulses, but when the relay V still holds the contact v_1 open, the 15 two branches of the talking line are likewise unsymmetrical. Thus a test coil C of a testing selector connected in parallel with the switch arms J_1 and J_2 of the illustrated selectors could obtain current in the following circuit, viz: ground, contact s_1 in the first selector I GW, resistance w_6 , contact v_2 , a -branch of the trunk line, contacts a_4 , c_4 , switch arm J_1 , multiple connection, contact arm of the testing selector, coil C , second 20 contact arm of the testing selector, multiple connection, b -branch of the trunk line, contact p_2 in the illustrated second selector II GW, contacts k_3 , a_3 , relay B_2 , battery and ground. In order to keep this current very 25 small the retardation relay V in the first selector opens the contact v_2 and connects the resistance w_5 into this circuit. This resistance w_5 is so large that the current flowing through the test coil of a testing selector is 30 too small to energize the testing relay C . The holding circuit for the excitation of the relay A_2 over the contact s_1 in the second selector is, however, maintained in spite of the resistance being cut in.
- 35 Also, during the rotation of the second selector there would be want of symmetry on the two branches of the line. The b -branch is currentless because the relay B_2 is entirely disconnected from it. The contact v_1 will 40 have closed some little time after the second selector has started to move. The condition is then as follows: a current flows on the a -branch from ground in the first selector I GW, over contact s_1 , resistance w_6 , over the 45 now closed contact v_2 , a -branch of the talking line, contact p_1 in the second selector II GW, resistance w_4 , relay A_2 , battery and ground. The contact k_2 is now open and the contact b_7 is likewise open as the relay B_2 50 will have released its armatures. The b -branch is grounded in the first selector at the contact s_1 , but it is broken in the second selector at the contacts b_3 and k_3 . If a coil is connected in parallel to the contact arms 55 J_1 and J_2 while this condition exists, a current will flow through the test coil C connected in parallel from the ground, battery in the second selector II GW, relay A_2 , resistance w_4 , contact p_1 , multiple connection, 60 test coil C , multiple connection, contact arm 65

J_2 and back to the ground in the illustrated first selector. The resistance w_4 now prevents a sufficiently powerful current for the test relay from flowing, while on the other hand this resistance w_4 admits of a holding 70 current sufficient for holding the relay A_2 .

Let it now be assumed that the third selector has found a free connector. A connector is free when the a -branch of the trunk line is connected to the battery in similar manner as in the selectors and when the b -branch is connected to ground. The test coil P_{31} of the third selector and the relay A_4 in the connector attract their armatures, that of the relay A_4 disconnecting the b -branch of the trunk line from the ground at a_8 and connecting the relay B_4 over the contact a_9 to the battery. The relays A_4 and B_4 are thus energized. When the subscriber now rotates his dial for the third time the 75 relay X in the first selector is energized. The contacts x_4 and x_5 are closed and the contact v_1 is opened. During the interruptions of the loop in the dial switch the b -branch is kept alive, so that the relay B_4 80 remains energized during the emission of impulses in the following circuit, viz: ground, battery, relay B_4 , contacts y_1 , b_8 and p_7 , b -branch of the trunk line, switch arms J_6 , J_4 , J_2 , contacts c_5 , x_4 , ground. This circuit over the b -branch keeps the relay B_2 in the second selector energized because the relay B_2 is connected over the contact p_4 and the coil P_2 to the b -branch. Consequently, when the interruptions in the dial 85 switch cause the a -branch to be currentless in consequence of the contact a_4 being opened in the first selector, the second selector remain stationary nevertheless because the releasing circuit was closed only at the 90 same time as the relay B_2 released its armatures. The current in the b -branch and the simultaneous absence of current during the impulse in the a -branch causes the relay A_4 in the connector to release its armature 95 while the relay B_4 remains energized. The following circuit for the lifting magnet H_4 of the connector is thereby established, viz: ground, battery, lifting magnet H_4 , contacts u_1 , a_9 , b_9 , ground, and the connector shaft is 100 lifted. At the termination of the impulses the relay X releases its armatures, the contacts x_4 and x_5 are opened, the contacts v_1 of the relay V remaining open for a time. A current now flows over the a -branch from 105 ground in the first selector I GW; contact s_1 , resistance w_6 , resistance w_5 , contacts a_4 , c_4 , switch arm J_1 , a -branch of the trunk line, contacts p_5 , p_6 , relays P_1 and A_2 in the 110 second selector II GW, battery, ground, in the third selector III GW over switch arm J_8 , relay A_3 , battery, ground and, in addition, in the connector over switch arm J_5 , contact p_8 , resistance w_8 , contact y_2 , relay A_4 , battery and ground. In the second selector 115 120 125 130

tor, besides the relay A_2 the relay P_1 also remains energized although its coil P_2 has become currentless. Consequently, the relays A , A_2 , A_3 and A_4 are energized.

- 5 The connection into circuit of the resistances w_4 and w_8 has the same object of causing the busy condition as described for the second selector. Owing to the b -branch in the connector being currentless the relay B_4 10 releases its armature. The relay U' is thereby energized over the following circuit, viz: ground, battery, relay U' , contact a_{10} , b_{10} , the contact k_5 closed at the first lifting step of the connector LW, ground. The relay 15 U' closes its make contact u_2 and remains energized independently of the state of the relay B_4 until the connector opens the contact k_5 again when falling back into its normal position. The relay U' changes the contact u_1 over to u_3 . When the relay V in the 20 first selector releases its armature a moment later, the contact v_1 is closed and the b -branch is grounded again and current flows again over ground in the first selector 25 I GW, contact s_1 , resistance w_7 over the b -branch, contact p'_2 , relay P_2 , contact p_4 , relay B_2 , battery, ground to the relay B_3 in the second selector, and also over switch arms J_4 , J_6 , contacts p_7 , a_9 , y_1 , relay B_4 , battery, ground. The relays B_2 , B_4 attract 30 their armatures. When the subscriber rotates his dial again the relay X also attracts its armature. The contact x_4 in the first selector closes again and the contact v_1 is opened again. The current remains in the 35 b -branch of the trunk line because it is grounded over the contact x_4 . The current in the a -branch is interrupted just as frequently as the contact a_4 in the first selector 40 is opened in consequence of the interruptions in the dial switch. Each time the circuit is broken the relay A_2 in the second selector and the relay A_4 in the connector become currentless. The current in the 45 second selector produces no effect, but in the connector the rotary magnet is energized in the following circuit, viz: ground, battery, rotary magnet D_4 , contacts u_3 , a_9 , b_9 and ground. Simultaneously with the rotary magnet D_4 the retardation relay V_4 is 50 also energized over ground, battery, relay V_4 , contacts u_3 , a_4 , b_9 and ground.
- When the relay X is currentless again after sending the last series of impulses, the 55 contact x_4 in the first selector opens, but the contact v_1 remains still open, and the b -branch thus becomes currentless again. The relay B_4 in the connector releases its armatures. The relay V_4 in the connector still 60 remains energized, however, in consequence of its retardation. A testing current for the connector then flows from ground over contacts g_1 , m_3 , v_3 , b_{11} , relay P_3 , testing arm of the connector, break contact of the pre- 65 selector VW' of the called subscriber N_2 ,
- separating relay T_2 , to the battery. The testing relay P_3 of the connector is energized. After some time the contact v_1 in the first selector will close again. The relay B_4 in the connector is thereby energized again. 70 The testing relay P_3 of the connector remains energized, however, because it has connected itself over its make contact p'_7 into a holding circuit and has short-circuited a part of the winding of the relay P_3 , 75 whereby the called line is rendered busy. On the test relay P_3 being energized the contact p'_8 is made and the contact p_7 broken. The relay A_4 remains energized over the contact y_2 , resistance w_{11} , contact 80 p'_8 a -branch of the trunk line and either over contact x_4 or over resistances w_5 , w_6 and contact s_1 to ground. The b -branch is currentless at this moment. If the relay V in the first selector then releases its armature 85 and closes the contact v_1 current will flow again over the b -branch in the following circuit, viz: ground, contact s_1 , resistance w_7 , b -branch of the trunk line, resistance w_{10} in the connector, contact a_9 , contact y_1 , relay 90 B_4 , battery, ground. It is of no importance whether the relay B_4 is energized over the resistance w_{10} or not as when both relays A_4 and B_4 neither simultaneously attract their armatures nor remain deenergized, no further consequences occur. The bridge in the connector thus runs over the a -branch of the trunk line, contact p'_8 , resistance w_{11} , contacts y_2 , relays A_4 , B_4 , contacts y_1 , a_9 or contact b_8 , resistance w_{10} , b -branch of the 100 trunk line. As soon as the test relay P_3 has attracted its armature it closes a contact p_9 in the circuit of a calling relay L and contacts p_{10} and p_{11} in the line. While the relay V_4 is still energized in consequence of its 105 retardation a first calling current is produced for the called subscriber in the following circuit, viz: ground, battery, coil 2 of the relay L , contacts v_4 , p_9 , y_3 , k_6 and ground, the contact k_6 having closed at the 110 first lifting step of the connector. The relay L breaks the contact l_1 and l_3 and makes the contacts l_2 and l_4 , and thereby at the moment of testing sends a calling current to the called subscriber. When the relay V_4 has 115 released its armature additional periodic impulses of calling current are sent owing to the excitation of the coil 1 of the relay L over ground, battery, interrupter U_4 , coil 1, contacts p_9 , y_3 , k_6 and ground. This periodic calling current lasts until the called subscriber lifts his receiver. A circuit is thereby made as follows, viz: ground, relay F , contacts l_1 , p_{10} , the called line, contacts p_{11} , l_3 , coil 1 of the relay Y , battery 120 and ground. The relays F and Y in this circuit attract their armatures. The relay Y first interrupts the calling current by opening the contact y_3 and making the contact y_4 and energizing its (very weak) hold- 125
- 65 selector VW' of the called subscriber N_2 , 130

ing coil 2 over ground, battery, coil 2, contacts y_4 and k_6 , and ground, this coil 2 being deenergized at the release of the connector even when the called subscriber prematurely 5 replaces his receiver. The relay Y also breaks the contacts y_2 and y_4 and makes the contacts y_5 and y_6 . The relays A_4 and B_4 now release their armatures. Instead thereof of an inductively wound relay O, having the 10 middle of its winding grounded, is connected into circuit. The coils of this relay are wound inductively, *i. e.* non-differentially. The ground at the relay O in the connector is now in parallel with the ground at the 15 contacts s_1 in the first selector at the talking branches of the trunk lines. The bridge in the second and, under certain circumstances, also in the third selector provides the battery for the further excitation of the relays 20 A_2 , B_2 , A_3 , B_3 in the selectors. The resistances of the coils of the relay O and the resistances w_{11} , w_{10} in the connector are so great, however, that the relay O cannot attract its armature.

25 In case the called subscriber should not be disengaged the test relay P_3 of the connector cannot be energized. The talking wires are then not connected through at the contacts p_{10} , p_{11} and the calling subscriber 30 receives a buzzing signal over a shaft contact wh_3 and the contact p_{12} . In the illustrative embodiment the connector does not return into its normal position, but the testing circuit remains open as the relay V_4 35 opens the contact v_3 after a short time.

Let it be assumed that the called subscriber replaces his receiver before the calling subscriber. The relay F is then deenergized. The relay Y remains energized, 40 however, over its holding coil Y_2 . The following circuit for a relay G is closed, viz: ground, battery, relay G, contacts y_7 , f_1 and ground. The relay G breaks the contact g_1 and opens the circuit of the relay P_3 . The 45 contacts p_{10} and p_{11} and p_7 open. The called subscriber thereby becomes perfectly free. He can be called by another party, and can himself call although the connector still remains on his line. When the calling subscriber 50 replaces his receiver the relays A and B in the first selector are deenergized. On the relay B being deenergized the contact b_{12} closes and the relay S is thereby energized in the following circuit, viz: 55 ground, contact b_{12} , the contact k_7 , closed at the first lifting step of the first selector, relay S, battery and ground. The conversation which has taken place is now metered and the connection is then done away with. 60 In the first selector the ground is disconnected at the contact s_1 , and by closing the contact s_3 of the relay S a meter relay Zr in the first selector is connected into circuit. The ground at the relay O is now the 65 sole ground connection in the connector and

must therefore now supply current for the meter bridge in the first selector and for the bridge-connected relays A_2 , B_2 in the second, and the relays A_3 , B_3 in the third selector. The current in the relay O is thereby 70 strengthened to such an extent that the relay O attracts its armatures. The meter relay Zr in the first selector operates at the same time, however. This relay Zr closes its contact zr_1 in the selector and thereby 75 short-circuits the resistance w_1 . The current in the testing line C thereby increases to such an extent that the meter Z is energized over the following circuit, viz: ground, battery, contact t_1 , meter Z, c -line, 80 contacts zr_1 , s_2 , wh_2 , m_2 and ground. When the short circuit of the contact s_2 over the relay C in the first selector has acted for a time the relay C releases its armature. The contacts c_4 and c_5 are thereby opened and 85 the switch arms J_1 , J_2 are separated from the apparatus in the selectors. At the same time the following circuit for the releasing magnet of the first selector is closed, viz: ground, battery, magnet M, contacts s_4 , b_{13} , 90 c_6 , ground. This circuit is opened again only on the arrival of the shaft of the selector into its normal position when the circuit for the relay S has been opened at contact k_7 , and the contact s_4 is subsequently 95 broken. When the releasing magnet M is energized it opens the contacts m_1 and m_2 . The holding current for the cut-out magnet T of the preselector or line switch VW is thereby interrupted whereupon this switch 100 returns into its normal position.

The connector is released owing to the relay O being energized. The following circuit containing releasing magnet M_4 is thereby closed, viz: ground, battery, magnet M_4 , contacts y_9 , o_1 , ground. When the shaft of the connector arrives into its normal position the contacts k_5 , k_6 and k_8 are opened. The relays U' and Y are thereby deenergized and the releasing magnet M_4 110 likewise becomes currentless. As soon as the relay Y is deenergized the relay O is disconnected at the contacts y_5 and y_6 . The battery is again connected over the relays A_4 and B_4 to the trunk line and now the 115 trunk line is not grounded at all either in the first selector or in the connector. The bridges in the selector are therefore currentless. In the second selector the releasing circuit is closed over ground, battery, releasing magnet M_2 , contacts a_{11} , p_3 , b_5 , k_4 , ground, and in the third selector over ground, battery, releasing magnet M_3 , contacts a_{12} , p_{13} , b_{14} , k_9 and ground. These circuits remain established until the shafts of 120 the selectors open the contacts k_4 and k_9 on its arrival into its normal position. All the switching apparatus have then been returned into their normal positions.

If the required subscriber has not lifted 130

his receiver or if the desired subscriber's line was engaged metering is prevented as follows. In this case the relay Y is not energized. The relay O is thus not connected to the trunk line. Under these circumstances, when the calling subscriber replaces his receiver the relays A and B in the first selector become currentless, the relay S is energized and ground is cut off at the contact s_1 . The relay Zr is not energized, however, because in the connector no reversal of the battery over the relays A₄ and B₄ to ground over the relay O has taken place. Under these circumstances the battery is still connected to the trunk line in all the selectors. The selectors at once begin to release in consequence of the trunk line being currentless and the relays A₄ and B₄ also release their armatures. As mentioned above, the relay B₄ may be already deenergized, but in any case the relay A₄ is now also deenergized. The following releasing circuit in the connector is thereby now closed, viz: ground, battery, releasing magnet M₄, contacts y_8 , b_{15} , a_{13} , k_8 and ground. The contact k_8 is broken when the shaft of the connector has returned into its normal position.

I claim:—

1. In an automatic telephone system comprising telephone lines, trunk lines each having two talking wires, and switches and selectors for interconnecting said telephone lines with trunk lines, the combination with the trunk lines of test relays associated with the trunk lines and having coils adapted to be connected at the one end to the one talking wire of the trunk line and the other end to the other talking wire, and means associated with the trunk lines for taking reduced potential to said talking wires when the trunk line is busy.

2. In an automatic telephone system comprising telephone lines, trunk lines each having two talking wires, and switches and selectors for interconnecting said telephone lines with trunk lines, the combination with the trunk lines of test relays associated with the trunk lines and having coils adapted to be connected at the one end to the one talking wire of the trunk line and the other end to the other talking wire, battery-conductors associated with the trunk lines for supplying testing potential to the talking wires, and resistances in said battery-conductors for reducing the test potential when the trunk lines are busy.

3. In an automatic telephone system comprising telephone lines, trunk lines each having two talking wires, and switches and selectors for interconnecting said telephone lines with trunk lines, the combination with the trunk lines of test relays associated with the trunk lines and having coils adapted to be connected at the one end to the one talking wire of the trunk line and the other end

to the other talking wire, battery-conductors associated with the trunk lines for supplying testing potential to the talking wires, resistances in said battery-conductors for reducing the test potential when the trunk lines are busy, and short-circuits associated with said battery-conductors for short-circuiting said resistances when the trunk line is free.

4. In an automatic telephone system comprising telephone lines, trunk lines each having two talking wires, and switches and selectors for interconnecting said telephone lines with trunk lines, the combination with the trunk lines of test relays associated with the trunk lines and having coils adapted to be connected at the one end to the one talking wire and at the other end to the other talking wire and adapted to produce in both talking wires an equal drop of potential for avoiding clicking noises during the testing process, and means associated with the trunk lines for taking reduced potential to said talking wires when the trunk line is busy.

5. In an automatic telephone system comprising telephone lines, trunk lines each having two talking wires, and switches and selectors for interconnecting said telephone lines with trunk lines, the combination with the trunk lines of test relays associated with the trunk lines and adapted to be connected to the talking wires, circuits associated with the trunk lines for producing a locking circuit in the one talking wire for locking and supervising the connection established by the selectors, holding relays for locking and supervising the connection, resistances in said circuits for producing a drop of potential when the line is occupied, said resistances being of such magnitude that the holding relays will retain their armatures and the test relays will not be energized, and means for producing a sending and change-over circuit in the other wire of the trunks.

6. In an automatic telephone system comprising telephone lines, trunk lines each having two talking wires, and switches and selectors for interconnecting said telephone lines with trunk lines, the combination with the trunk lines of test relays associated with the trunk lines and having coils adapted to be connected at the one end to the one talking wire of the trunk line and the other end to the other talking wire, two battery-conductors of equal potential each connected to one of the talking wires, and means associated with the trunk lines for changing the potential in one of said conductors when the trunk line is busy.

7. In an automatic telephone system comprising telephone lines, trunk lines each having two talking wires, and switches and selectors for interconnecting said telephone lines with trunk lines, the combination with the trunk lines of test relays associated with the trunk lines and having coils adapted to

be connected at the one end to the one talking wire of the trunk line and the other end to the other talking wire, two battery-conductors of equal potential each connected to one of the talking wires, a third battery-conductor of different potential, and a test relay in one of the two battery-conductors, the latter relay being adapted when energized to disconnect the battery-conductor of

one potential from the one talking wire and 10 to connect the battery-conductor of different potential to the same talking wire.

In testimony whereof, I affix my signature in the presence of two witnesses.

MAX LANGER.
